CLAIM

The ornamental design for a speaker dock as shown and described.

DESCRIPTION

FIG. 1 is a right front perspective view of a speaker dock showing an embodiment of the claimed design;

FIG. 2 is a front perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof;

FIG. 8 is a right view thereof; and,

FIG. 9 is a cross-sectional view along an A-A direction in FIG. 4 thereof.
